(57) **CLAIM**

The ornamental design for a loop chair, as shown and described.

DESCRIPTION

The present application is based on and claims priority to U.S. Design application Ser. No. 29/314,109, filed Mar. 3, 2009 in the name of William Pederson, under 35 U.S.C. §120, and entitled Loop Chair, the entire contents of which are hereby incorporated by reference.

FIG. 1 is a plan view of a loop chair showing my new design in accordance with a first embodiment;

FIG. 2 is a front elevation view of the loop chair of FIG. 1; FIG. 3 is a side elevation view of the loop chair of FIG. 1; and, FIG. 4 is a perspective view of the loop chair of FIGS. 1-3, as seen from the front and side of the chair.

The shadows in the drawings illustrate environmental structure and form no part of the design.
